UNITED STATES PATENT OFFICE.

CHRISTIAN AALBORG, OF PITTSBURGH, PENNSYLVANIA, ASSIGNOR TO WESTINGHOUSE ELECTRIC & MANUFACTURING COMPANY, A CORPORATION OF PENNSYLVANIA.

PANEL-BOARD BOX.

Application filed September 16, 1921. Serial No. 501,143.

My invention relates to panel boards and particularly to enclosed panel boards for distributing current to a plurality of separate circuits, such, for example, as circuits to a 5 plurality of separate motor or lighting units located in factories, apartment houses and the like.

One object of my invention is to provide a panel board, the essential elements of which 10 may be assembled in the factory as a unit and which may readily be placed in a suitable main housing at the location in which it is to be used and there constitute a complete enclosed panel board.

15 Another object of my invention is to provide a panel board wherein all live parts of the electrical devices and their connections are fully protected by an enclosure having suitable door-closed openings through which 20 different parts of the device are accessible, the doors being so disposed that they may be opened separately or simultaneously for the purpose of exposing only such devices as are to be operated or inspected.

25 Another object of my invention is to provide a panel board, having the above characteristics, wherein the complete unit comprises three separate compartments, namely, a switch compartment, a wiring gutter 30 rounding the switch compartment and an outer centrally-disposed compartment for enclosing the switch-operating handles, and wherein the wiring gutter is closed by a cover which may be detachably secured to the main 35 housing and which contains an opening through which the switch compartment and the outer compartment are accessible, the opening being closed by a main door having a door therein for closing an opening in the 40 main door through which the outer compartment only is accessible.

Another object of my invention is to provide a panel board wherein the main housing is provided with an enclosure for dividing 45 it into a wiring gutter and a switch compartment communicating through openings that are closed by switch panels provided with openings through which the conductors may extend from the switch compartment into the wiring gutter.

50 Another object of my invention is to provide a panel board wherein a housing for containing the switch mechanism, fuse devices, bus bars and connectors comprises a bottom pan and an enclosure device secured

thereto, and wherein metal stiffening devices serve in place of a solid slate or marble insulating base to support the switch panels.

Another object of my invention is to provide a panel board wherein the switch and 60 fuse devices are mounted on insulating panels within an enclosure and wherein a pan is disposed over the switch devices to make them inaccessible except when the pan is removed, the pan containing only the operating handles of the switches, and wherein the fuses are accessible only through a space 65 between the pan and the side of the enclosure which is closed by a main door, the door, however, being provided with an opening through which only the switch-operating handles within the pan are accessible and which is closed by a door hinged to the main door.

70 Another object of my invention is to provide a panel board wherein the metal parts not normally in the circuits are grounded with the housing, thus permitting the use of metal switch handles and eliminating the necessity for expensive insulation between 75 the switch supports, pan and housing walls.

80 A further object of my invention is to provide a panel board wherein the different elements are disposed in compact relation and may readily be assembled, inspected and repaired.

85 These and other objects, that will be made apparent throughout the further description of my invention, are attained by means of the panel board hereinafter described, and 90 illustrated in the accompanying drawings, wherein:

Figure 1 is a front plan view of a complete panel board unit without the cover;

Fig. 2 is an elevational view, partially in section and partially in elevation, of the device shown in Fig. 1, with the cover in place, the section being taken on the broken lines II-II of Fig. 1;

Fig. 3 is a front plan view of the panel 100 board with the cover in place;

Fig. 4 is an elevational view of a fragment of the device shown in Fig. 1, the section being taken on the broken line IV-IV of Fig. 1;

Fig. 5 is a sectional view of an alternative pan-supporting device, the section being taken on the line V-V of Fig. 1;

Fig. 6 is a front plan view of a section of a panel board having two bus bars;

Fig. 7 is an end view of the apparatus shown in Fig. 6.

Fig. 8 is a fragmental sectional view taken on the line VIII—VIII of Fig. 2 showing the bottom pan and partition in elevation,

Fig. 9 is a fragmental section of the outer pan taken on the line IX—IX of Fig. 1, and

Fig. 10 is a fragmental sectional view taken on the line X—X of Fig. 1 showing the bottom pan and an end partition wall in elevation.

Referring to the drawings, the panel board includes a main housing 8 that is constructed of sheet metal, the side walls thereof being provided with inwardly turned flanges 9 to which the cover 11 is secured by means of screws 12.

A sheet metal pan 13, that is provided with marginal flanges 14, is centrally disposed within the main housing and is attached to the bottom of the housing 8 by screws 15.

An enclosure, having side walls 16 and 17 of substantially the same contour as the flanges 14, is disposed within the housing in superimposed relation with respect to the flanges and serves to divide the main housing into an outer compartment or wiring gutter 18, which completely surrounds the enclosure, and an inner or switch compartment 19 within which the switch panels and bus bars are mounted.

The lower edges of the wall members 17 are provided with rectangular notches 21 (see Fig. 4) for the purpose of providing openings between the inner edges of the wall members and the outer edges of the flanges 14 through which the ends of the insulating panels 22, that are mounted in the switch compartment 19, extend into the wiring gutter 18. The purpose of this arrangement will hereinafter appear.

Heretofore, it has been common practice to mount the switch panels upon an insulating base of slate, marble or other insulating material, secured to, and substantially covering, the bottom of the main housing. This construction is heavy, and expensive for the reason that numerous holes are required for attaching the slate to the housing and for supporting attaching devices for the panels.

In the present construction, a relatively small slate base 23 is employed for supporting the terminals and bus bars of the feed circuits, which extends entirely across one end of the pan 13 but does not cover that portion of the pan occupied by the switch panels. Z bars 24 are secured to the bottom of the pan 13 and extend longitudinally thereof at right angles to the base a sufficient distance to support any desired number of switch panels 22 and serve to support them in spaced relation from the bottom of the pan 13 at such elevation that the inner faces of the panels lie flush with the outer face of the insulating base 23.

The panels 22 are attached to the Z bars 24 by means of screws 25 and 26 which extend through perforations in the panels 22. The screws 26 serve to attach the supports of the switches 27 to the panel 22 and also serve to conductively connect the support to the Z bar in such manner that the switch support is grounded with respect to the main housing.

As shown in Fig. 1, the switch panels 22 are disposed in rows on opposite sides of the enclosure 19, and the outer ends thereof extend through the notches 21 in the walls 17 and are provided with grooves 28 that are formed between projecting ridges 29 and lugs 31 which are cast integral with the insulating panel 22.

The panels serve to close the openings 21 and are each provided with two perforations or openings 32 which provide passages through which conductors 33 may extend from the wiring gutter 18 into the switch compartment where they are attached to terminals 34 that are connected to threaded metallic socket members 35 which constitute receptacles for screw-plug fuses of standard construction. The panels serve to support the lower edges of the wall members 17 and provide an insulated passage through which the conductors 33 may enter the switch compartment 19.

The panels 22, shown on the right-hand side of Fig. 1, are provided with fuse-clip terminals 36 for receiving cartridge fuses in place of the plug fuses, both forms of fuse receptacles being shown to illustrate the adaptability of the panel arrangement to fuses of either type. The switches 27, shown in Figs. 1 and 2, are of the tumbler type fully illustrated and described in my co-pending application, Serial No. 415,772, filed Oct. 9, 1920, but it will be understood that switches of any preferred type may be employed. The switches are mounted on the inner ends of the panels 22. The terminals thereof are connected to bus bars by terminals 37 which are connected to bus bars 38, 39 and 40 by means of supporting conductors 41, 42 and 43, respectively, of U-shape which are adapted to support the bus bars in superimposed spaced relation, as indicated in Figs. 1 and 2.

The supporting conductors 41, 42 and 43 also serve to connect the switch terminals on one side of the switch compartment to corresponding terminals of the switches mounted on the panels disposed on the opposite side of the switch compartment. The ends of the bus bars are suitably bent to engage the outer face of the slate base 23 and are secured thereto by means of screws 44. Each bus bar is provided with a terminal member 45 to which the feed conductors of a three-conductor circuit are attached. The wall member 16 of the enclosure, adjacent the terminals 45, is provided with an opening 46 that is closed by means of an insulating plate 47 that is provided with circular openings 48.

which register with the ends of the terminals 45 and through which the feed wires extend into the switch chamber. The plate 47 is disposed on the inner side of the wall member 16 and extends to the outer edge thereof for the purpose of so insulating the wall member 16 in the immediate vicinity of the terminal members 45 that it shall afford protection against causing a short-circuit should 10 a screw driver, or other metal implement, come into contact with the wall member while the terminals are being adjusted.

In order to provide a chamber in which only the operating handles of the switches 37 are accessible, a pan or partition 49, having outwardly extending marginal flanges 51, is mounted within the switch compartment in superimposed relation to the switches. The pan is so disposed that it provides a space 52 20 between the flanges 51 thereof and the wall members of the enclosure and through which the fuses and fuse receptacles are accessible, and serves to substantially cover the switches 27, the bus bars 38, 39 and 40 and the conductor supports 41, 42 and 43.

The under side of the pan or partition 49 is indented, as at 53, Figs. 1, 2 and 9 adjacent openings 50 for receiving projections 54 mounted on the extreme outer ends of the 30 switch support 30. Lateral displacement of the pan with respect to the switch supports is prevented, and the pan is conductively connected to the switch support by reason of the engagement of the projections 54 with 35 the bottom of the pan.

The pan is supported, at one end, by means of supporting standards 55 which are secured to the bottom of the pan by means of screws 56 and, at the end adjacent the slate base 23, by means of similar supporting standards 57 that are attached to the slate base by means of screws 58 (see Fig. 4). In some instances, however, the standards 57 may be dispensed with and the end of the pan adjacent the slate base is then supported by means of an insulating tube 59 which is secured to the pan 49 by screws 60 and to the panel 22 that is adjacent to the slate base by means of screws 61, as indicated in Fig. 5. 50 By reason of this construction, the necessity for drilling holes in the slate base, in which sockets for the retaining standards 57 are embedded, is eliminated.

The operating handles 62 of the switches 55 27 are made of metal and are grounded with respect to the main housing through the switch support 30 by the attaching screws 26, or through the supporting standards 55. The use of the metal handle is perfectly safe 60 under such conditions and is inexpensive in construction.

Referring to Fig. 3, the main cover 11 is provided with an opening 63 that is substantially the same size as the switch compartment 19 and through which all of the

apparatus within the switch compartment is accessible. The opening 63 is closed by a door 64 that is hinged, at one side of the cover 11, by means of hinges 65 and is provided with a latch 66 which may be key- 70 actuated, if preferred. The door 64 is provided with an opening 67 substantially the size and contour of the pan 49 through which only the switch-operating handles 62 are accessible. The opening 67 is adapted to be 75 closed by a door 68 that is hinged to the door 64 by means of hinges 69 and is provided with a latch 71 that is similar to the latch 66.

It will be seen from the foregoing that, 80 when the door 68 is open, the switch handles 62 only are accessible, and that, when the door 64 is open, only the fuse receptacles and fuses are accessible through the spaces 52 on opposite sides of the pan 49.

In order to gain access to the switch, the pan 49 must first be removed. When it is desired to gain access to the wiring gutter 18, the cover 11 is removed by first removing the attaching screws. 90

In panel boards of this type, it is intended to assemble all of the mechanism within the switch chamber at the factory and to install the complete ensemble within the main housing 8 after the latter has been placed in the 95 wall of the building in which the apparatus is to be used. For this reason, the pan 13 and the wall members 16 and 17 are attached to one another by means of corner plates 72, which engage the outer faces of the flanges 14 100 and the wall members 16 and 17, and corner plates 73 which engage the inner faces of the flanges 14 and the wall members 16 and 17.

The plates 72 and 73 are drawn together by means of screws 74 which securely clamp 105 the wall members and the pan in assembled relation. The corner plates 72 are provided with integral extensions 75 which constitute attaching lugs to be secured to the bottom of the housing 8 by means of bolts 76. The 110 pan and wall members 16 and 17 are made of such size as to accommodate any desired number of panels and, while only two panels are shown in the device illustrated in Fig. 1, any number of panels may be accommodated by extending the length of the enclosures and correspondingly extending the bus bars along the entire row of panels. 115

The flanges 51 of the pan 49 are joined at the corners by means of corner plates 77 120 which are arcuate in shape and provide rounded corners for the pan. The corner plates also serve to support the corners of the free edge of the door 68. The pan is also provided, adjacent each switch handle which projects through the opening 50, with three up-struck projections 79, Figs. 1 and 9, which are sheared through the plate and serve as seats for identification cards 81 upon which are printed appropriate legends indicating 125 130

the circuits controlled by the switch. The cards are inserted at the upper ends of the end projections 79 and are detachably retained by means of a rib 82 that is indented 5 from the underside of the pan.

In Figs. 6 and 7, I have shown a modified bus bar structure wherein two bus bars 83 and 84 for a two-conductor circuit are provided to extend longitudinally of the panel 10 in superimposed relation. The switch terminals 37 are connected to the bus bars by means of the supporting conductors 85 and 86 which serve, in a manner similar to the supporting conductors 41, 42 and 43 previously referred to, to support the bus bars and, at the same time, connect corresponding terminals of the switches disposed on opposite sides of the bus bars.

The bus bars are bent inwardly into engagement with the insulating base 23 and are secured thereto by means of screws 44, in a manner similar to the means for attaching the bus bars 38, 39 and 40 to the three-pole circuit. The bus bars 83 and 84 are connected to terminals 87 and 88, respectively, which are adapted to be connected to the feed conductors.

While I have shown no main switch, it will be understood that, where no main switch 30 is provided outside of the main housing, any preferred form of main switch may be mounted upon the insulating base 23 and connected between the feed-conductor terminals and their respective bus bars. Where 35 a main switch is located within the main housing, the only change necessary is to increase the longitudinal dimensions of the housing and the width of the insulating base 23.

40 It will be apparent from the foregoing that the construction illustrated and described provides a simple and compact panel box wherein the different elements thereof are arranged to provide convenience of operation and assembly and to provide absolute safety, it being impossible for unauthorized persons to come in contact with live conductors.

Where the door 64 is locked with a key-50 actuated lock, only the compartment 60 containing the operating handles is accessible to patrons of the building in which the panel board is installed. The latch 71 may be provided with a key-actuated lock to preclude 55 operation of the switches except by authorized persons.

While I have described and illustrated but one embodiment of my invention, it will be apparent to those skilled in the art that various changes, modifications, substitutions, 60 additions and omissions may be made in the apparatus illustrated without departing from the spirit and scope of the invention, as set forth in the appended claims.

65 I claim as my invention:

1. A panel board comprising a main housing, a pan within the housing having outwardly extending flanges, panel members mounted on the pan and having a portion thereof overlapping the said flanges, and a wall member of 70 substantially the same contour as the said flanges and disposed in substantially superimposed relation thereto and extending inwardly into engagement with the said panel for dividing the main housing into an inner and 75 outer compartment.

2. A panel board comprising a bottom pan, an enclosure member having side walls conforming in contour to the side walls of the pan and terminating adjacent the edges of the pan, the said adjacent edges of the side walls being cut away to provide openings between the edges of the pan and side walls, and panel members mounted on the pan and closing the 80 said openings, the said panel members being 85 provided with openings through which conductors may extend exteriorly of the enclosure member.

3. A panel board comprising a bottom pan, 90 an enclosure member having side walls conforming in contour to the side walls of the pan and terminating adjacent the edges of the pan, the said adjacent edges of the side walls being cut away to provide openings between 95 the edges of the pan and side walls, means for attaching the enclosure member to the pan, stiffening members secured to the bottom of the pan, and panel members mounted on the stiffening members in spaced relation to the bottom of the pan and closing the said openings, the said panel members being provided with openings through which conductors may extend exteriorly of the enclosure member.

4. A panel board comprising a bottom pan, 100 an enclosure member having side walls conforming in contour to the side walls of the pan and terminating adjacent the edges of the pan, the said adjacent edges of the side walls being cut away to provide openings between 110 the edges of the pan and side walls, means for attaching the enclosure member to the pan, stiffening members secured to the bottom of the pan, and panel members mounted on the stiffening members and extending exteriorly 115 of the side walls of the pan and provided with means for engaging the walls of the enclosure member for preventing relative lateral displacement of the panel members and the walls of the enclosure member.

5. A panel board comprising a bottom pan, 120 an enclosure member having side walls conforming in contour to the side walls of the pan and terminating adjacent the edges of the pan, the said adjacent edges of the side walls being cut away to provide openings between 125 the edges of the pan and the side walls, means for attaching the enclosure member to the pan, an insulating base secured to the bottom of the pan and extending laterally thereacross, stiffening members 130

secured to the bottom of the pan and extending substantially at right angles to the insulating base having panel-supporting devices substantially flush with the outer face of the base and panel members supported upon the stiffening members and substantially closing the openings in the side walls of the enclosure member, the said panel members having openings through which the conductors may extend exteriorly of the housing.

6. A panel board comprising a bottom pan, an enclosure member having side walls conforming in contour to the side walls of the pan and terminating adjacent the edges of the pan, means for attaching the end-closure member to the pan, an insulating base secured to the bottom of the pan and extending laterally thereacross, stiffening members secured to the bottom of the pan and extending longitudinally of the pan and having panel-supporting devices substantially flush with the outer face of the base, bus bars attached to the base and extending longitudinally of the pan and in superimposed relation, panel mem-

bers mounted on the stiffening members and 25 on opposite sides of the bus bars, electrical devices on the panel members and means for connecting the electrical devices to the bus bars.

7. A panel board comprising a bottom pan, 30 an enclosure member having side walls conforming in contour to the side walls of the pan and terminating adjacent the edges of the pan, the said adjacent edges of the side walls being cut away to provide openings between 35 the edges of the pan and side walls, stiffening members secured to the bottom of the pan, and panel members mounted on the stiffening members in spaced relation to the bottom of the pan and substantially closing the said 40 openings, the said panel members being provided with openings through which conductors may extend exteriorly of the enclosure member.

In testimony whereof, I have hereunto subscribed my name this 31st day of August, 45 1921.

CHRISTIAN AALBORG.
